DRIVE CONSTRUCTION FOR MECHANICAL PENCILS

Carl Merryman, Melrose Park, Ill., assignor to
Dur-O-Lite Pencil Company, Melrose Park, Ill.,
a corporation of Delaware

Application January 30, 1951, Serial No. 208,487

4 Claims. (Cl. 120—18)

1

This invention relates to a new and improved mechanical pencil construction and more particularly to a construction which insures positive feed of the lead when the pencil has been filled with lead and assembled for use.

A well known form of pencil comprises a lead guide tube having a spiral opening in the wall and having a plunger or follower fitting in the tube with a portion projecting through the spiral opening and fitting in a longitudinal groove in an enclosing barrel. Relative rotation between the barrel and guide tube serves to move the follower downwardly of the tube to feed the lead out the lower end of the tube. Manufacturing tolerances are such that if the user merely drops the follower into the guide tube and does not feed it into the spiral before re-assembling the pencil when refilling it with lead, the follower may fail to feed into the spiral or may jam at the upper end of the spiral.

It is an object of the present invention to provide a pencil of this character having means for positively feeding the follower into the spiral when the parts are assembled.

It is a further object to provide such pencils with internal guide means at the upper end thereof whereby the follower is guided and forced into the spiral as the parts are assembled.

It is an additional object to provide such a construction which will operate efficiently with the parts varying in size throughout the range of normal manufacturing tolerances.

It is also an object to provide a pencil which is simple in design and adapted for commercial production and use.

Other and further objects will appear as the description proceeds.

I have shown certain preferred embodiments of my invention in the accompanying drawing in which—

Figure 1 is an elevation of a complete pencil;

Figure 2 is a longitudinal section of the upper portion of the pencil on an enlarged scale;

Figure 3 is a cross section taken on line 3—3 of Figure 2;

Figure 4 is a cross section taken on line 4—4 of Figure 2 and

Figure 5 is a cross section taken on line 5—5 of Figure 2.

In the drawing the pencil is shown as having a barrel 11 with an upper reduced portion 12 on which is fitted cap 13. These parts may be made of plastic or other suitable material and the cap is normally secured permanently in place by an adhesive or plastic solvent or other

2

desired means. The tip 14 is provided with slots 15 so that it resiliently grips the lead 16. The tip 14 is frictionally held in assembled relation to the barrel by conventional means forming no part of the present invention and not shown.

The spiral guide member 18, shown in Figure 2, is secured to the tip 14 and is rotated by rotation of the tip to feed the lead downwardly by means of the mechanism shown. This mechanism comprises a follower 20 having an outwardly bent portion 21 and a downwardly bent portion 22, the portion 21 passing between the turns of the spiral guide member 18. This portion 21 preferably has its upper and lower surfaces flattened on inclined planes corresponding to the pitch of the spiral opening in member 18.

The hollow barrel 11 is provided with one or more longitudinally extending internal grooves 24 adapted to receive the downturned portion 22 of the follower 20. The groove 24 into which this portion of the follower is fitted prevents the follower from rotating relative to the barrel. Thus when the spiral guide 18 is rotated relative to the barrel by turning the tip 14 upon the barrel the follower or plunger 20 is fed downwardly, forcing the lead 16 downwardly through the resilient grip of the split tip 14.

The general pencil construction described above has been used heretofore and in itself forms no part of the present invention.

In the use of such pencils the lead is renewed by pulling the tip 14 away from the barrel, the tip bringing with it the spiral guide 18 and the follower 20. The follower 20 is held against rotation by the fingers and the tip 14 together with the member 18 are rotated to cause member 20 to rise out of member 18. A new lead is dropped into member 18 and the plunger 20 dropped upon the lead. The member 18 is then replaced in the barrel with the portion 22 of member 20 fitting in a groove 24. The barrel 11 and tip 14 are then given relative rotation to move follower 20 down to force the lead downwardly until a suitable length projects beyond tip 14 for use.

These pencils are produced in large quantities and it is impractical in production to manufacture the parts with such close tolerances that the upper end of spiral member 18 makes a close fit with the under face of the cap 13. The intermediate portion 21 of the follower 20 may rest on the upper edge of the member 18 or may be held above that edge by contact with the lead when the parts are reassembled. There may be sufficient clearance between the top member 18 and the under face of cap 13 so that the portion 21

merely rides around on top of member 18 when the parts are given relative rotation. If it does not enter the spiral in member 18 the lead is not fed down and the pencil is inoperative.

The members 18 are cut from continuous spiral lengths and the upper edge will have a comparatively sharp point above the spiral opening as indicated at 27 in Figure 5. If there is a clearance between the under face of the cap 13 and the upper edge of member 18, which clearance is of less dimension than the thickness of portion 21 of the follower 20, this portion 21 may become jammed in the point 27 when the parts are thrust together and given relative rotation.

According to the present invention the inner face of the cap 13 is provided with a cup shaped member 29 having a central downwardly extending lug 30 adapted to fit within the upper end of member 18. The lateral walls 32 of the cup 29 have their inner edge chamfered to form a sloping or conical surface, as shown at 34, to engage the outer edge of portion 21 of the follower 20.

The combination of lug 30 and chamfered edge 34 engages the upper face and outer edge of portion 21 of follower 20 when the parts are assembled with this portion resting on the upper edge of member 18 and the member 18 is thrust upwardly into the barrel 11. The tip 14 is turned relative to the barrel 11 as the parts are inserted and the portion 22 of member 20 is held against rotation by the groove 24. As the upward thrust and turning motion is continued the lug 30 and chamfered edge 34 force the member 20 downwardly into the spiral opening in the member 18 as soon as the portion 21 of member 20 reaches that opening. Thus the member 20 is fed down the spiral and cannot fail to enter the spiral and cannot become jammed at the upper end of the spiral.

It will be understood that the construction shown may be varied to meet differing conditions or requirements. For example the lug and chamfered edge may be formed integrally with the cap rather than as an insert in the cap. I therefore contemplate such modifications as come within the spirit and scope of the appended claims.

In the claims:

1. A mechanical pencil comprising a barrel, a lead guide tube having a spiral opening formed in its walls, a tip permanently secured to the lead guide tube and frictionally fitted on the lower end of the barrel, the lead guide tube and tip being jointly removable from the lower end of the barrel, the barrel being tubular and having an inner longitudinal groove, a follower fitted in the guide tube and having a portion extending through the spiral opening and into the barrel groove, the follower being removable from the upper end of the guide tube to permit insertion of lead in said tube, the barrel having a closed upper end, the inner face of the upper end having a lug extending downwardly therefrom and into the upper end of the guide tube.

2. A mechanical pencil comprising a barrel, a lead guide tube having a spiral opening formed in its walls, a tip permanently secured to the lead guide tube and frictionally fitted on the lower end of the barrel, the lead guide tube and tip being jointly removable from the lower end of the barrel, the barrel being tubular and having

an inner longitudinal groove, a follower fitted in the guide tube and having a rounded portion extending through the spiral opening and into the barrel groove, the follower being removable from the upper end of the guide tube to permit insertion of lead in said tube, the barrel having a closed upper end, the inner face of the upper end having a lug extending downwardly therefrom and into the upper end of the guide tube, the inner face also having a sloping circumferential portion adapted to engage the portion of the follower extending outwardly of the spiral guide.

3. A mechanical pencil comprising a barrel, a lead guide tube having a spiral opening formed in its walls, a tip permanently secured to the lead guide tube and frictionally fitted on the lower end of the barrel, the lead guide tube and tip being jointly removable from the lower end of the barrel, the barrel being tubular and having an inner longitudinal groove, a follower removably fitted into the guide tube, said follower having a portion extending downwardly in the tube, an intermediate portion extending through the spiral opening in the guide tube and an outer downwardly extending portion fitting in the inner groove in the barrel, the intermediate portion of the follower having its upper and lower faces formed to conform to the pitch of the spiral in the guide tube, the follower being removable from the upper end of the guide tube to permit insertion of lead in said tube, the barrel having a closed upper end, the inner face of the upper end having a downwardly extending lug fitting loosely within the guide tube.

4. A mechanical pencil comprising a barrel, a lead guide tube having a spiral opening formed in its walls, a tip permanently secured to the lead guide tube and frictionally fitted on the lower end of the barrel, the lead guide tube and tip being jointly removable from the lower end of the barrel, the barrel being tubular and having an inner longitudinal groove, a follower removably fitted into the guide tube, said follower having a portion extending downwardly in the tube, an intermediate portion extending through the spiral opening in the guide tube and an outer downwardly extending portion fitting in the inner groove in the barrel, the intermediate portion of the follower having its upper and lower faces formed to conform to the pitch of the spiral in the guide tube, the follower being removable from the upper end of the guide tube to permit insertion of lead in said tube, the barrel having a closed upper end, the inner face of the upper end having a downwardly extending lug of circular cross section fitting loosely within the guide tube, said inner face also having a conical circumferential portion adapted to engage the upper face of the portion of the follower extending outwardly of the spiral guide.
